UNITED STATES PATENT OFFICE

2,461,345

PLAYGROUND SLIDE

Gordon W. Packer, Litchfield, Mich., assignor to
Litchfield Manufacturing Company, Litchfield,
Mich., a corporation of Michigan

Application December 3, 1945, Serial No. 632,313

7 Claims. (Cl. 272—56.5)

1

The present invention relates to a play slide assembly and more particularly to such assemblies having novel safety and constructional features.

Play slides of the character described are conventionally constructed of wood and are of such design as to be unsafe for use by children. According to the present invention, the slide assembly is of all steel construction thereby eliminating the possibility of splinters. Furthermore, there is provided a standing platform below the extreme top of the slide providing a safety pocket in which children using the slide may stand, rather than at the extreme top where they are more likely to fall. The slide also provides a novel hand rail cooperating with the structural design of the slide to provide additional safety features and the entire structure is readily portable.

It is, therefore, an object of the invention to provide a safety play slide having the aforesaid novel features either all in combination, or separately, as desired.

Another object of the invention is to provide a play slide having access steps pivoted thereto for increasing the portability of the slide.

A further object is to provide a safety step at the top of a play chute.

A still further object is to provide a play chute having a novel hand rail.

These and other objects residing in the arrangement, combination and construction of the parts will be apparent from the following specification when taken with the accompanying drawings, in which

Fig. 1 is a perspective view of the invention.

Fig. 2 is a sectional view of the chute taken at a point intermediate to upper and lower ends.

Fig. 3 is an enlarged view of the upper end of the chute.

Fig. 4 is a perspective view showing the bare chute and steps folded together and the hand rail removed.

Referring particularly to the drawings, the reference character 1 indicates a chute preferably of sheet metal having a load supporting portion 2 and side guiding rails 3. The chute 1 is provided with the usual lower portion 4 at a lesser angle to the horizontal than the main portion of the chute for the purpose of checking speed. At this lower portion of the chute 1 are provided supports 5.

The upper portion 6 of the chute 1 has disposed on each side thereof, a gusset plate 7 which has edges 8 in alignment with the guiding rails 3 and other edges 9 extending at an angle substantially

2

less than 180° from the direction of the edges 8. While it is convenient to use gusset plates 7, gusset plates as such are not essential and it is therefore contemplated that in the claims where the term "gusset plate" is used, equivalent devices are included, such as one or more tie bars (not shown), for example.

The guiding rails 3 have secured as by welding directly to the upper edges thereof hand rails in the form of tubular pipe 10. The pipe 10 extends along the edges 8 and 9 of the gusset plate 7 continuously from the guiding rail 3. The pipe 10 has the advantage of providing a smooth, non-splintering, safety hand rail and at the same time providing a considerable degree of stiffening to the chute. The plates 7 may be welded to the rail 3 and the pipe 10 may be welded to the edges 8 and 9 of the plates 7.

The upper portion 6 of the chute 1 is supported in an elevated position by steps 15 which include side rails 16. The side rails 16 are pivoted about pins 17 to the gusset plates 7 so as to permit the steps 15 to pivot into the position shown in Fig. 4. This feature of the invention permits the ready folding up of the slide for transportation and storage purposes. The pipes 10 on the edges of the gusset plates 7, away from the chute edges, serve as stops to opening pivotal movement of the steps 15 with respect to the chute 1.

A safety feature of the invention of considerable importance resides in the positioning of the upper step 20. The step 20 is supported by the gusset plates 7 and is provided with a riser 21 which intersects directly the load supporting portion 2 of the chute 1. The step 20 together with the riser 21 and gusset plates 7 provide a pocket in which a user of the slide stands just previous to stepping into the chute 1 for sliding down the same. The pocket has the result of supporting a user of the slide somewhat below the uppermost position and gives lateral support by virtue of the riser 21 and gusset plates 7. Thus a user of the slide is less likely to fall than should the uppermost step be disposed at the extreme top of the chute 1 as is conventional. The riser 21 may be integral with the load supporting portion 2 of the chute or may be a separate member welded in position. The steps 15 are provided with safety hand rails 25, secured at the lower end to the side rails 16 and at the upper end to the gusset plates 7. The connection between the rails 25 and the gusset plates 7 is made through a metallic disc 26, one being secured to the inside of each rail 25 at a position opposite its adjacent gusset plate 7. A bolt 27 extends through the two gusset

plates 7 and the disc 26 to clamp the discs 26 to the gusset plates 7. When the slide is folded as shown in Fig. 4, the hand rail 25 may be first removed along with the disc 26 by removing the bolt 27.

While a specific form of the invention has been disclosed, defining the particular features of the invention, it is contemplated that the features of the invention may be incorporated in other specific slide forms. Accordingly, I do not wish to be limited except by the scope of the following claims.

Having thus described my invention, what I desire to secure by Letters Patent and claim is:

1. A play slide assembly comprising a chute having a load supporting portion and side guiding rails having upper edges, a gusset plate at each side of one end of said chute, said gusset plates having edges in alignment with said guiding rails and extending in one direction, said plates having edges extending in parallel relation in another direction at an angle substantially less than 180° from said first-named direction, a step supported by said gusset plates, a riser for said step supported by said gusset plate and intersecting directly said load supporting portion of said chute, said step and riser forming a safety pocket for users of the slide to stand, in a position below the top of said chute, and means to support said gusset plate end of said chute in an elevated position, said supporting means including means to provide access to said first-named step.

2. The invention as defined in claim 1 wherein hand rails in the form of tubular pipes are secured to the upper edges of said guiding rails, said hand rails extending along aforesaid edges of said gusset plates respectively.

3. A play slide assembly comprising a chute having a load supporting portion and side guiding rails having upper edges, a gusset plate at each side of one end of said chute, said gusset plates having edges in alignment with said guiding rails and extending in one direction, said plates having edges extending in parallel relation in another direction at an angle substantially less than 180° from said first-named direction, a step supported by said gusset plates, a riser for said step supported by said gusset plates and intersecting directly said load supporting portion of said

chute, said step and riser forming a safety pocket for users of the slide to stand, in a position below the top of said chute, hand rails secured to said upper edges of said guiding rail, steps to support said gusset plate end of said chute in elevated position, and means to pivot said steps to said gusset plate.

4. The invention as defined in claim 3 wherein said hand rails on the second named edges of said gusset plates are disposed in normal position against said steps, whereby said portions of said hand rails serve as stops to prevent pivotal movement of said steps.

5. A play slide assembly comprising a chute having a load supporting portion, means to support one end of said chute in an elevated position, a step spaced downwardly from the upper end of said chute and in alignment with the longitudinal axis thereof, and a riser for said step intersecting directly with the load supporting portion of said chute, whereby said step and riser form a pocket for users of the slide to stand in, in a position below the top of said chute, and the intersection of said riser with the load supporting portion of said chute discourages the standing by users of the chute at the extreme upper portion thereof as a safety measure.

6. The invention as defined in claim 1 wherein there are provided means for pivoting said supporting means to the gusset plates.

7. The invention as defined in claim 1 wherein the supporting means is in the form of a ladder and there is provided means for pivoting the ladder to the gusset plate.
